MINE CAR SAFETY STOP

Bud E. Kirtner, Eules Barker, Marshall Williams,
and Ashlon Jackson, Chattooy, W. Va.

Application March 18, 1948, Serial No. 15,544

1 Claim. (Cl. 104—257)

1

This invention relates to a mine car safety stop.

It is an object of the present invention to provide a mine car safety stop which can be easily applied to a rail and upon the sleepers and which is so shaped when thrown onto the top of the rail that there is little opportunity for the wheels of the car to avoid the stop or for the same to become injured or bent and wherein there is provided clamp elements for fixing the unit to the rail besides fixing it to the sleepers.

Other objects of the present invention are to provide a mine car safety stop for rails which is of simple construction, inexpensive to manufacture and efficient in operation.

For other objects and for a better understanding of the invention, reference may be had to the following detailed description taken in connection with the accompanying drawing, in which

Figure 1 is a side elevational view of our safety stop,

Figure 2 is an end elevational view of the safety stop with the wheelchock pulled from the rail,

Figure 3 is a top plan view of the stop with the wheelchock in place upon the rail as in Figure 1,

Figure 4 is a sectional view of the stop, in elevation, taken on line 4—4 of Figure 1,

Figure 5 is a fragmentary sectional view taken on line 5—5 of Figure 4,

Figure 6 is a detail sectional view taken on line 6—6 of Figure 4.

Fig. 7 is a detailed sectional view showing the manner of connecting the safety stop to the rails and

Fig. 8 is a fragmentary detailed view of the connecting lever for the connecting links.

Referring now to the figures, 10 represents a rail which is mounted on sleepers 11 in the usual manner. Beneath this rail and connected to the sleepers is the mine stop unit 12 of the present invention. Our mine stop unit comprises a base 13 having cornered holes 14 through which spikes 15 are extended for securing the unit to the sleepers 11. Before driving the spikes, the base 13 is securely clamped to rail 10. On the top of the base are clamp elements 16 having portions adapted to extend over the bottom flange of the rail, Figure 2. These clamp elements are fixed to the base by screws 17 and 18. On the opposite side of the rail and of the base are laterally swingable clamp elements 19 having a curved engaging face 21 adapted to be

2

brought onto the rail in a wedge-like manner. The clamps 16 have upstanding flanges 22 which have cam surfaces 22' which bear against the head of the rail as seen in Figs. 2 and 4.

5 Pivoted on the side of the base 13 as indicated at 25, Figure 4, is a link 26 which is pivotally connected by a pin 27 with a link 28 that is coupled by an eye bolt 29 to the wheelchock 23. A pin 31 extends through the link 28 and the eye bolt 29 and is held in place by cotter pins 32. A handle 33 is secured to the link 28 by bolts 34. This handle has a projection 35 for retaining the links 26 and 28 in their extended positions with the wheelchock 23 raised. On the link 26, there

15 may be fixed an arm 36 by bolts 37 by means of which connection can be made with a safety stop disposed on the opposite rail so that the two stops can be operated together. Such connection being accomplished by connecting one end 20 of the link 46 in each opening 47 in the arm 36 and then connecting the opposite ends of the links in the opposite end of the lever 48. The lever 48 being pivotally mounted at 49 on the bracket 50 fixed to the side of the sleeper 11.

25 This arm 36 is so formed that it may abut the bottom face of the base 13 and thereby limit the drop movement of the links 26 and 28 by pulling outwardly on the handle 33, the wheelchock 23 can be pivoted to the drop position shown in Figure 2. Upon lifting the handle it can be thrown into its operative position shown in Figure 4.

30 The wedge elements 19 are pivotally connected to the base 13 by pivot bolts 41 and are retained in wedging engagement with the side of the rail 10 by cotter pins 42 which are extended into the base 13.

35 The wheelchock 23 has an upwardly extending portion 43 which extends upwardly beside the rail 10 when the wheelchock is in its raised position. From this portion 43 there extends an offset portion 44 with which car wheel 45 engages, Figure 4.

40 While various changes may be made in the detail construction, it shall be understood that such changes shall be within the spirit and scope of the present invention as defined by the appended claim.

We claim:

45 A car stop comprising a base, clamp elements on said base adapted to engage the bottom flange on one side of a rail, pivoted clamp elements on the base opposite to said first clamp elements that are adapted to be pivoted to engage the bottom flange of the rail on the opposite side thereof to retain the base in fixed relation to the bottom

flange of the rail, upstanding flanges on said first clamp elements, cam surfaces on said upstanding flanges adapted to bear against the head of the rail, a wheelchock pivoted upon said flanges and adapted to be extended into operative position upon the rail or retracted to inoperative position laterally of the rail, lower and upper links pivoted respectively to the base and to the wheelchock and to one another for retaining the wheelchock in position on the rail, an operating handle on the upper link whereby said links may be operated for controlling the position of the wheelchock, an arm connected to the lower link, and a control linkage connected to the arm and to a similar car stop on the adjacent rail, whereby said linkage may be actuated to simultaneously move both wheelchocks from operative to inoperative positions.
